UNITED STATES PATENT OFFICE.

HANS P. VON NOSTITZ, OF NEW YORK, N. Y.

DESIGN FOR BRAID.

SPECIFICATION forming part of Design No. 36,847, dated March 8, 1904.

Application filed February 6, 1904. Serial No. 192,457. Term of patent 7 years.

To all whom it may concern:

Be it known that I, HANS P. VON NOSTITZ, a citizen of the United States, residing in New York, borough of Brooklyn, and State of New York, have invented a new, original, and ornamental Design for Braids, of which the following is a specification.

The nature of my design is fully represented in the accompanying drawing, to which

reference is made and which shows in elevation 10 a braid embodying my design.

I claim as my invention—

The ornamental design for a braid, substantially as shown.

HANS P. VON NOSTITZ.
